UNITED STATES PATENT OFFICE

2,581,036

BRASSIÈRE

Evelyn McIlhinney, Ottawa, Ontario, Canada

Application November 6, 1947, Serial No. 784,401

3 Claims. (Cl. 2—42)

1
This invention relates to improvements in a brassière or other foundation garment and appertains particularly to one designed to correct the posture by drawing the shoulders back and raising the bust and generally enhance the carriage and appearance of the wearer.

An object of the invention is to provide a brassière, bandeau, corselette or other foundation garment having supporting straps passing over the shoulders with special means to draw the shoulders back and simultaneously raise and separate the breasts.

A further object of the invention is to provide a simple, posture-improving shoulder brace combined with a bust supporting garment, wherein the shoulder straps of the garment are adjustably laced together at the back to give the desired draw to the shoulders while supporting the breasts in raised and separated position.

A further object of the invention is to provide a brassière type of garment with shoulder-straightening means, the adjustment of which automatically equalizes with the bust-supporting feature to compensate for the raising and separating of the breasts incidental to the shoulders being drawn back and the chest expanded.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 is a rear view of a preferred embodiment of my posture-improving brassière;

Figure 2 is a front view thereof;

Figure 3 is a front perspective view of a modified form of shoulder straightening brassière wherein the breast cups are joined by a stretchable band;

Figure 4 is a similar view of a further modified form wherein a stretchable insert occurs in the body encircling band and continues up between the breast cups;

Figure 5 is a modified view of the back of a garment, similar to that shown in Figure 1, but

with separate adjusting laces for the shoulder straps and body encircling band respectively;

Figure 6 is a variation of that shown in Figure 5, the ends of the body encircling band being releasably connected by a hook and eye with one part being on a stretchable member;

Figures 7 and 8 show further modified forms of garments, the backs of the shoulder straps being adjustably drawn together by a lacing 10 through vertically spaced loops on confronting edges of the straps and a pair of longitudinally adjustable cross straps, respectively; and

Figure 9 is a rear perspective elevation of a corselette-type combination garment, embodying the present invention, with a tension-adjusting draw lace threaded through the shoulder straps at the back.

Women with rounded or stooped shoulders and heavy, weakened or sagging breasts usually tire more quickly than those that sit and stand erect and are possessed of generally good posture. Neither back braces to correct round shoulders nor bust uplift supports alone are adequate to produce a perfect posture and are not infrequently awkward and uncomfortable. The marked raising and separating of the breasts as the shoulders are straightened clearly indicates the close relation between shoulder straightening and bust support in attaining perfect posture with its increased vitality and better health. Moreover, the full grace of the female form is only reached when the carriage is correct, the head and shoulders erect and the bosom comfortable and high.

In the present shoulder straightening, bust supporting invention, the garment comprises essentially a pair of breast receiving cups or pockets 1 and 2 attached at their lower edges to a body encircling band 3 and a pair of shoulder straps 4 and 5 extending one from the top of each of the cups 1 and 2 to the back of the body encircling band 3. The confronting ends 3a and 3b of the band 3 terminate short of each other and on opposite sides of the vertical median and are variously connected under tension. The preferred form of band 3 seen in Figures 1 and 2 has a vertical row of eyelets 6 down each end 3a and 3b and includes also a triangular pleat 7, for form shaping, at the centre of the front thereof. The breast cups 1 and 2 attaching to the band along their lower edges are also connected to each other as at 8 for a short distance up from the band at the front median and in vertical line with the apex 45 of the pleat 7. The firm supporting straps 4

and 5 extending from the cups 1 and 2 and designed to pass over the shoulders of the wearer connect to the band 3 on either side of the central gap and at points spaced substantially in from the respective ends 3a and 3b of the said band. These stout shoulder straps each include a row of vertically spaced eyelets 9 running up from their juncture with the said band and a common lace 10 is threaded through both these strap eyelets 9 and the band eyelets 6 by which the garment is snugly and comfortably adjusted to the person of the wearer. As the lace is drawn to the desired tightness, the shoulder straps 4 and 5 are pulled together, as seen in Figure 1, causing the wearer's shoulders to straighten and the whole body to assume a more erect and proper posture. Co-incidental with the straightening of the shoulders, the raising of the bosom and the separating of the breasts that occurs is matched by a simultaneous equalizing lifting and spreading of the garment's cups 1 and 2, produced by the added tension on the straps and permitted by the cups' vertical independence of each other except for the short length of interconnection at the junction 8.

In the modified form shown in Figure 3 the cups 11 and 12 attach at the bottom to the band 13 but do not connect to each other at all. Instead a horizontal stretchable member 14 extends between the cups at a distance above the band and about mid-way of their height. In the embodiment seen in Figure 4 the band 23 is severed in the mid-front and a panel 24 of stretchable material is inserted that rises above the band to lie between and attach to both of the cups 21 and 22. Both these forms thus make added provision for the separating and/or lifting of the breasts that occur when the shoulder straps are drawn together at the back as by a lace as hereinbefore described.

Instead of using a single lace to draw the shoulder straps and body encircling band ends together as shown in Figure 1, it may be desired to thread the lace 10 through only the eyelets 9 in the shoulder straps 4 and 5 and to employ a second and independent lace 10a, threaded through the band eyelets 6 as in Figure 5, to tighten the band 3. Obviously the use of two laces allows of the separate adjustment of each but the lacing of both the shoulder straps and body band ends together with a single one has the obvious advantage of equalizing.

The idea of separately lacing just the shoulder straps 34 and 35 together, as by an independent lace 30, is carried further in Figure 6 where the spaced ends of the body band 33 at the back are separately connected by a cooperating hook-and-eye assembly 36, one part of which is on a length of stretchable material 37.

In Figures 7 and 8 the body bands 43 are each fastened at the back by conventional hooks and eyes but the shoulder straps 44 and 45 in the former are provided with inwardly reaching fabric loops 46 at spaced intervals from the top of the band 43 upwards and the lace 47 is threaded through these loops. A shorter lace suffices and the threading of it is simplified. The shoulder straps 54 and 55 in Figure 8 are provided with two or more vertically spaced, transversely adjustable, horizontal straps 56 and 57. While this arrangement allows of drawing the backs of the shoulder straps 54 and 55 together in varying degrees at different levels,

it lacks too some of the advantages of the preferred design with the single equalizing lace.

The adaptation of the invention to a combination garment such as the corselette 60 shown in Figure 9 is a normal carrying forward of the basic idea, for here the upper edge 61 of the back of the garment is substantially equivalent to the body band 3 in Figure 1 and the shoulder straps 64 and 65 are similarly provided each with a vertical row of spaced eyelets 66 extending up from the top edge of the back of the garment and an adjustable lace 67 is threaded therethrough.

Better health and greater energy mark the wearers of this combination shoulder brace and bust support. Likewise the user is graced with enhanced appearance, better carriage and poise and the general sense of well being that accompanies proper posture.

From the foregoing description taken in connection with the accompanying drawings, it will be manifest that a brassière is provided that will fulfill all the necessary requirements of such a device, but as many changes could be made in the above description and many apparently widely different embodiments of the invention may be constructed within the scope of the appended claims, without departing from the spirit or scope thereof, it is intended that all matters contained in the said accompanying specification and drawings shall be interpreted as illustrative and not in a limitative or restrictive sense.

Having thus described the invention, what I claim as new and desire to secure by Letters Patent is:

1. A posture-improving bust supporting garment comprising a body encircling band having spaced ends at the back thereof, a pair of breast-receiving cups attached to said band on opposite sides of its front median, a pair of laterally spaced shoulder straps extending one from the top of each of said cups to the back of said body band and secured thereto in spaced relation to the respective ends thereof, a row of vertically spaced eyelets in each end of said band and a row of vertically spaced eyelets in the back of each of said shoulder straps above said band and an adjustable draw lace threaded through said eyelets in said shoulder straps and said band ends.

2. A posture-improving bust supporting garment for straightening the shoulders and lifting the breasts of the wearer, comprising a body encircling band having opposite ends spaced from each other and connectable at the back of the wearer, a pair of breast receiving pockets attached to the band along opposite sides of its front median, said pockets being connected together at their lower edges and being relatively free and movable with respect to one another for the remainder of their length; a pair of laterally spaced shoulder straps extending one from the upper portion of each of said pockets to the back of said band and secured thereto at a point spaced laterally from the respective ends thereof, said straps and said band being provided with

means for receiving a single fastening means, and a single fastening means connecting said straps and said band and passing through said receiving means, the tightening of said fastening means pulling said straps together at the back and straightening the shoulders of the wearer, and simultaneously lifting the breast receiving pockets to raise the breasts of the wearer.

3. A garment according to claim 2, wherein the fastening receiving means are eyelets and the fastening means comprises a draw lace threaded

through the respective eyelets, being first threaded through the shoulder straps.

EVELYN McILHINNEY.
